UNITED STATES PATENT OFFICE.

DAVID E. ROSS, OF LA FAYETTE, INDIANA, AND ORLANDO GARRISON, OF DAYTON, OHIO; SAID ROSS ASSIGNOR TO SAID GARRISON.

MEANS FOR DRESSING GRINDING-WHEELS.

1,366,285.

Specification of Letters Patent. Patented Jan. 18, 1921.

Original application filed July 14, 1917, Serial No. 180,566. Divided and this application filed January 17, 1918. Serial No. 212,259.

To all whom it may concern:

Be it known that we, DAVID E. Ross and ORLANDO GARRISON, citizens of the United States, said Ross residing at La Fayette, county of Tippecanoe, State of Indiana, said GARRISON residing at Dayton, in the county of Montgomery and State of Ohio, have invented certain new and useful Improvements in Means for Dressing Grinding-Wheels; and we hereby declare that the following is a full, clear, and exact description thereof, reference being had to the accompanying drawings, which form part of this specification.

This invention relates to machines for grinding the teeth of gears by means of an emery wheel or other suitable grinding wheel having its edge dressed to pressure angle of tooth to be generated as described in our original application filed July 14th, 1917, Serial No. 180,566.

The object of the present invention is to provide novel means for adjusting the diamonds, or other means for dressing the grinding wheel so that it can be trimmed or dressed in exactly the desired manner; and to provide micrometer adjustments and setting for the diamonds.

We will explain the invention with reference to the accompanying drawings which illustrate one practical embodiment and application of the invention, and an understanding thereof will enable others to readily adopt and use the invention; and in the claims we summarize the essentials of the invention and novel features and combinations of parts, for which protection is desired.

In said drawings:

Figure 1 is a longitudinal sectional elevation of a gear grinding machine embodying the invention, partly broken away.

Fig. 2 is an enlarged side elevation of the gear supporting devices, and diamond adjusting devices.

Fig. 3 is a detail plan view of Fig. 2, with parts removed.

Fig. 4 is an enlarged vertical sectional view of the diamond setting devices. Fig. 5 is a transverse section thereof on line 5-5, Fig. 4. Fig. 6 is a section on line 6-6, Fig. 4.

The gear cutting machine in connection with which our invention is shown, com-

prises a base 1 provided with a support 8 55 for a sliding table 7 which carries the work supporting and adjusting devices, and the grinder, and the grinder dressing devices which latter embody the invention which we wish to protect herein.

This body 1 is provided with guides for a sliding member 2 which carries the grinding wheel 180 and the devices for adjusting this wheel relative to the work. Said member 2 also carries a micrometer bar 165, which is 65 used in setting the diamonds as hereinafter explained.

The member 2 is adapted to be reciprocated toward and from the work support by any suitable means.

The grinding wheel 180 is mounted on a spindle 25 which may be driven by any suitable means and said grinding wheel 180 is preferably adjustably and removably secured on the spindle 25. The spindle bearings are 75 preferably adjustable so that the spindle can be aligned with the utmost accuracy and truth in its bearings, and the wheel may be raised or lowered by turning the screw 163.

The sides of wheel 180 should be dressed 80 to the pressure angle of the gear to be generated, and the edge of the wheel in cross section should be duplicate of a rack tooth of the desired pitch and pressure angle.

The gears to be ground are mounted upon 85 a work spindle 135 (Figs. 1 and 5) which is preferably mounted in a head or bracket 4 on a carrier or work table 7 mounted on the main frame beneath the grinding wheel and movable transversely of the main frame and 90 on the outer end of the spindle is a master or pattern gear 185, which should be an exact duplicate of the gear to be ground, and which may be removably secured on the spindle in any suitable manner so that it 95 cannot rotate thereon.

The master wheel 185 is adapted to be locked by a shot-bolt 170 attached to a slide 6, which is vertically movable in guides 37 attached to the main frame in front of the 100 guide 8. All the aforesaid parts are preferably constructed and adapted to operate as described in our aforesaid application.

The means for dressing the grinding wheel forms the subject matter of the present invention and application and, in the example 105 shown in the drawings such means are as follows:

The slide 7 has a rearward extension or bracket 7^a on which are mounted the devices for dressing the grinding wheel. A side dressing diamond 124 and an edge dressing diamond 124¹ are mounted respectively on the top and end of a horizontally adjustable slide 100, which is mounted to move horizontally in a vertically adjustable slide 101 attached to a slide 101^a, which is guided on a bracket 96^a attached to the upper end of a rotatable tubular support 96, which is rotatably mounted upon a sleeve 98, that is in turn mounted on a nut 114, screwed on a standard 97^a. Said sleeve 98 has a flange on its lower end engaging an annular recess in the nut 114 and is confined thereto by an annulus 99 secured by screws 121.

The standard 97^a has a base 97 mounted upon the bracket 7^a and secured by a nut 116 and pin 115. The support 96 is yielding held down upon the sleeve 98 by means of a spring 109 strung on a rod 106 extending into the standard 97^a and connected with a cap 107 closing the upper end of the support 96.

By rotating the nut 114, the sleeve 98 and the wheel dressing devices thereon can be raised or lowered. The sleeve 98 is slidable on the standard 97^a but is prevented from rotating on the standard 97^a by means of a key 208, engaging corresponding slots in the sleeve and standard, as shown, so as to permit the sleeve and support to be raised on the standard, but the sleeve cannot rotate thereon.

The support 96 may be turned on the sleeve to bring the diamond 124¹ into positions to engage either side of the grinder wheel 180 and when in proper position may be locked by suitable means. For this purpose the sleeve may be provided with notches 96^a, 96^b, 96^c, (see Figs. 3 and 5) arranged at the proper points, with any one of which a pin 108 may be engaged. The pin 108 may be guided in a tubular housing on the side of the support 96; said pin being movably pressed inward by a spring 113 as indicated in the drawings.

The slide 100 may be adjusted by means of a screw 104 and clamped by screw 118. The slide 101 may be adjusted by a rack 102^a on the slide engaging a pinion 103^b on the shaft 103 of a hand wheel 105.

Pin 108 is engaged with notch 96^a only when setting diamond 124 to height. Pin 108 must be either in slot 96^a or 96^c when used for dressing either sides or periphery of wheel. Diamonds after once set, require adjustment only occasionally to compensate for amount worn off diamond.

To dress outside diameter of wheel.—Place pin 108 in either the right or left notch 96^a or 96^c then screw wheel head 3 down until the periphery of grinding wheel

180 touches diamond 124; then pass diamond back and forth, by revolving handle 145, and continue to rotate wheel 180 until its periphery is in perfect condition.

To set diamond #124¹ and dress sides of wheel.—After the periphery of wheel is dressed; move slide 7^a handle 145 until the locating pin 144 engages the related hole in guide 8 to lock the slide. Then engage pin 108 with say notch 96^c; then raise the dresser slide 102 by means of hand wheel 105, until diamond 124¹ is opposite the side of grinding wheel; then adjust diamond 124¹ against the grinding wheel by operating screw 104; and gradually raise and lower slide 101 while the grinding wheel is rotated until the opposed beveled side of wheel 180 is properly dressed. Then turn dresser to opposite side of wheel and engage pin 108 with notch 96^a and operate diamond as before, until the grinding wheel is dressed to give correct pitch to teeth to be ground.

Summary of operations.

When the device is used in the machine shown in our aforesaid application to prepare grinding wheel we proceed as follows: We first ascertain the root radius of gear (which for example we assume is 38,554, the distance from center of work spindles to lower edge of wheel), then proceed as follows:

(1) Set micrometer 165 to 38,554. (2) Advance head 2 to forward end of stroke; this will bring the end 165^a of the micrometer bar 165 directly over diamond 124 when index pin 108 of dressing device is in slot 96^a; (3) raise diamond 124 into contact with end of micrometer bar by revolving nut 114; (4) turn support 98 until pin 108 engages slot 96^a; (5) move member 2 to extreme inner position to bring the center of the grinding wheel directly over diamond 124; leave member 2 in this position until the grinding wheel is dressed on its periphery and sides; (6) turn handle 188 to move the grinding wheel down to diamond; and then move the diamond back and forth under wheel by turning handle 145; continue to shift wheel 180 down until its periphery is perfectly dressed; (7) then turn handle 145 to bring slide 7 to central position and insert index pin 144 into index hole in part 8; (8) then move diamond 124¹ over to the grinding wheel by turning screw 104; then turn hand wheel 105, and move diamond up and down side of wheel; (9) then turn the support to move diamond to opposite side of wheel, and engage pin 108 in slot 96^c and move the diamond up and down; (10) continue reversing diamond from side to side of wheel and adjusting diamond until wheel is of proper width on face.

To redress the grinding wheel when worn, operate thereon in same manner and dress

the wheel on both sides and periphery. The index pin 144 should be engaged with the guide 8 when dressing the sides of the grinding wheel to insure that such wheel is absolutely central or in line with the work spindle. The original setting of the diamonds will dress the wheel to proper width and angle without any measuring, except to compensate for wear of the diamonds, which will be negligible.

What we claim is:

1. In combination a standard, a sleeve adjustably mounted on said standard, a support rotatably mounted on said sleeve, a vertically adjustable slide mounted on said support, a horizontally adjustable slide mounted on the vertically adjustable slide, and wheel dressing means carried by the horizontally adjustable slide.
2. In combination with a grinding wheel carrier, and a work carrier; of devices for dressing the grinding wheel comprising a standard mounted on said carrier, a support rotatably mounted on said standard, a vertically adjustable slide mounted on said support, a horizontally adjustable slide mounted on the vertically adjustable slide, and diamonds carried by the horizontally adjustable slide.
3. In combination with a grinding wheel carrier and a work carrier; of devices for dressing the grinding wheel comprising a standard mounted on said carrier, a sleeve adjustably mounted on said standard, a support rotatably mounted on said sleeve, a vertically adjustable slide mounted on said support, a horizontally adjustable slide mounted on the vertically adjustable slide, and diamonds carried by the horizontally adjustable slide.
4. In combination with a grinding wheel carrier and a work carrier; of devices for dressing the grinding wheel comprising a standard mounted on said work carrier, a sleeve slidably mounted on said standard, means for adjusting said sleeve, a support rotatably mounted on said sleeve, an adjustable slide mounted on said support, a diamond carried by said slide and a micrometer gage mounted on the grinding wheel carrier against which the diamond is adjusted preparatory to dressing the wheel.
5. In combination a standard, a sleeve adjustably mounted on said standard, a support rotatably mounted on said sleeve, a first slide mounted on said support, a second slide mounted on the first slide, diamonds carried by the second slide, means for adjusting the second slide horizontally relative to the first slide and means for adjusting the first slide vertically relative to the support.
6. In combination with a grinding wheel carrier and a work carrier; a standard mounted on said carrier, a sleeve adjustably mounted on said standard, a first vertically adjustable slide mounted on said standard, a second slide mounted on the first slide, diamonds carried by the second slide, means for adjusting the second slide horizontally relative to the first slide and means for adjusting the first slide vertically relative to the support.
7. In combination a grinding wheel carrier, a standard, a tubular support rotatably mounted on said standard, a vertically adjustable slide mounted on said tubular support, a horizontally adjustable slide mounted on the vertically adjustable slide, diamonds carried by the horizontally adjustable slide and means for vertically adjusting the support, means for rotatably adjusting and holding the support; and a micrometer gage mounted on the grinding wheel carrier against which the diamond is adjusted preparatory to dressing the wheel.
8. In combination a grinding wheel carrier, a standard, a sleeve adjustably mounted on said standard, a support rotatably mounted on said sleeve, a vertically adjustable slide mounted on said tubular support, a horizontally adjustable slide mounted on the vertically adjustable slide, diamonds carried by the horizontally adjustable slide and means for vertically adjusting the sleeve on the standard, means for rotatably adjusting and holding the tubular support on the sleeve; and a micrometer gage mounted on the grinding wheel carrier against which the diamond is adjusted preparatory to dressing the wheel.
9. In combination with a grinding wheel carrier and a work carrier; a standard mounted on said carrier, a sleeve adjustably mounted on said standard, a support rotatably mounted on said sleeve, a vertically adjustable slide mounted on said tubular support, a horizontally adjustable slide mounted on the vertically adjustable slide, diamonds carried by the horizontally adjustable slide, means for vertically adjusting the sleeve on the standard, and means for rotatably adjusting and holding the tubular support on the sleeve.
10. In combination with a grinding wheel carrier, a standard adjacent said carrier, a sleeve adjustably mounted on said standard, a support rotatably mounted on said sleeve, a vertically adjustable slide mounted on said support, a horizontally adjustable slide mounted on the vertically adjustable slide, a diamond carried by the horizontally adjustable slide, means for vertically adjusting the sleeve on the standard, means for rotatably adjusting and holding the tubular support on the sleeve, and a micrometer gage mounted on the grinding wheel carrier and against which the diamond is adjusted preparatory to dressing the wheel.

11. Means for dressing a grinding wheel, comprising a standard, a tubular support fitted over and rotatably mounted upon said standard, vertically and horizontally adjustable slides mounted on said support, and wheel dressing means carried by one of said slides.
12. Means for dressing a grinding wheel, comprising a standard, a tubular support fitted over and rotatably mounted upon said standard, a vertically adjustable slide mounted on said support, a horizontally adjustable slide mounted on said vertically adjustable slide, and wheel dressing means carried by the latter slide.
13. Means for dressing a grinding wheel, comprising a standard, a vertically adjustable member mounted on said standard, a tubular support fitted over and rotatably mounted upon said member, means for vertically adjusting the member on the standard, wheel dressing means adjustably mounted on said support, and means for locking the support to the member when adjusted.
14. In combination with a grinding wheel carrier and a work carrier; of means for dressing the grinding wheel, comprising a standard mounted on said work carrier, a support rotatably mounted upon said standard, a vertically adjustable slide mounted on said support, a horizontally adjustable slide on the vertically adjustable slide, and diamonds carried by the horizontally adjustable slide.
15. Means for dressing a grinding wheel, comprising a standard, a vertically adjustable sleeve mounted on said standard, a tubular support fitted to and rotatably mounted on said sleeve, and adjustable wheel dressing devices on said support.
16. Means for dressing grinding wheels, comprising a standard, a vertically adjustable sleeve mounted on said standard, a tubular support fitted to and rotatably mounted upon said sleeve, an adjustable slide mounted on said support, and wheel dressing means carried by said slide.
17. Means for dressing grinding wheels, comprising a standard, a vertically adjustable sleeve mounted on said standard, a tubular support rotatably mounted on said sleeve around and exterior to the standard,
- adjustable wheel dressing means on said support, means for vertically adjusting the sleeve on the standard; and means for locking the support on the sleeve.
18. In combination with a grinding wheel carrier and a work carrier; of devices for dressing the grinding wheel comprising a standard mounted on said work carrier, a vertically adjustable sleeve mounted on said standard, a tubular support rotatably mounted on said sleeve around and exterior to the standard, an adjustable slide mounted on said tubular support, and diamonds carried by said slide.
19. In combination with grinding wheel support and a work carrier; of devices for dressing the grinding wheel comprising a standard mounted on the work carrier, a support rotatably mounted on said standard, vertically and horizontally adjustable wheel dressing means on said support, and a micrometer gage mounted on the grinding wheel support and against which the wheel dressing means is adjusted preparatory to dressing the wheel.
20. In combination with a grinding wheel carrier and a work carrier; of devices for dressing the grinding wheel comprising a standard mounted on said work carrier, a support rotatably and vertically adjustably mounted on said standard, an adjustable slide mounted on said support, a diamond carried by said slide and a micrometer gage mounted on the grinding wheel carrier against which the diamond is adjusted preparatory to dressing the wheel.
21. In combination with a grinding wheel support, and a work support; of devices for dressing the grinding wheel comprising a standard mounted on the work support, a vertically adjustable sleeve mounted on said standard, a support rotatably mounted on said sleeve, adjustable wheel dressing means on said support, and a micrometer gage mounted on the grinding wheel support and against which the wheel dressing means is adjusted preparatory to dressing the wheel.

In testimony that we claim the foregoing as our own, we affix our signatures.

DAVID E. ROSS.
ORLANDO GARRISON.
